AUXILIARY CHAFFING DEVICE

Adolph Woehlert, Milwaukee, Wis.

Application April 8, 1939, Serial No. 266,835

3 Claims. (Cl. 130—22)

My invention relates to chaffing devices and more particularly to an auxiliary chaffing device adaptable to grain separators commonly known as threshing machines.

The object of my invention is to provide an auxiliary chaffing device that will permit the kernels of grain to be separated from the larger chaff and straw joints before engaging the conventional chaffer in the machine.

Another object of my invention is to construct the device that it may be applied to any existing separator without a great amount of mechanical changes or may be built into a separator at a very nominal cost.

A still further object of my invention is to provide a means that will permit the grain to fall through the device and to construct the device in a manner to provide a graduated support for the chaff in its travel rearward to the blower.

It is manifest to anyone familiar with grain separating devices that the chaff descending from the straw rack very often fills the adjustable chaffing devices to a degree where the grain cannot find its way through the chaffer in its horizontal travel from the conveyor. By employing the auxiliary chaffer described herein it makes it possible for the grain and small chaff to disintegrate and find its way to the regular adjustable chaffing device, the auxiliary chaffer merely acting as an additional means for separating the grain kernels from the chaff thereby saving the grain that would otherwise be carried with the straw or chaff to the blower and through the blower to the stack.

Other and further objects of my invention will become more apparent as the description proceeds when taken in conjunction with the drawings in which—

Figure 1 is a perspective view of the auxiliary chaffing device adaptable to all types of separators.

Figure 2 is a plan view of the arrangement of the blades and the manner in which they are spaced.

Figure 3 is a side view of Figure 2.

Figure 4 is a fragmentary perspective view of a portion of the projecting blades taken at line 4—4 in Figure 3.

Figure 5 illustrates in cross-section a method of separating and retaining the blades in position by means of sleeves.

Figure 6 is a fragmentary assembly showing the arrangement of the various parts of a grain separator and illustrating the manner in which the auxiliary chaffer is installed and,

Figure 7 is a fragmentary drawing illustrating the auxiliary chaffer and its relation to adjoining parts of the separator mechanism.

Similar characters of reference indicate corresponding parts through the several views and referring now to the same the character 10 in Figure 1 shows an auxiliary chaffer consisting of a plurality of blades 11, 12 and 13 held in longitudinal alignment with one another by means of rods 14. The blades 11, 12 and 13 respectively are all provided with upwardly projecting members 15 at their tops, these members are arranged in a manner to permit the chaff or the like to be pushed rearward by the feeding mechanism, at the same time preventing an accumulation of the chaff. The blades 11 extend the entire length of the device and have their depending ends corrugated at 16 to prevent any whip action due to the vibration. The blades 12 are disposed at approximately two-thirds of the length of the device while the blades 13 are only one-third of its entire length. All blades are retained in a separated position by means of sleeves 17 placed over the rods 14 as shown in cross-section in Figure 5. This arrangement provides a portion of the auxiliary chaffer having the blades relatively close together yet far enough apart to permit the grain to drop through. A second portion has the blades twice the distance apart as the first portion of the chaffer and a return portion having the blades arranged in a manner that provides four times the space as the first portion.

The entire device 10 is provided with suitable hanging members 18 which permit it being supported at a slight angle in any conventional type of separating assembly as shown in Figure 6 in which the straw rack 19 carries the straw to which the grain is attached into the separator, as it passes along the rack 19 the grain and chaff dropped through onto a conveyor shown as 20 and the return pan 21 catches the grain shaken by the rear of the rack 19 and returns it to the conveyor. Normally in a conventional type of separator the conveyor 20 carries the grain directly onto the adjustable chaffer 22 but by placing my device into use it is only necessary to lower the chaffer 22 and place the auxiliary chaffer 10 in direct line with the conveyor 20 at one end and raising the depending end of the auxiliary chaffer 10 to bring it at a slight angle thereby permitting the chaff which descends between the blades 11, 12 and 13 of the auxiliary chaffer 10 to contact the adjustable chaffer 22 and accumulate thereon as it is

forced by the blower over the adjustable chaffer extension 23. In this manner the chaff and grain delivered from the conveyor 20 first contacts the auxiliary chaffing device 10 which permits the grain to drop through with the smaller chaff to the adjustable chaffer 22 preventing thereby the carrying of the grain with the chaff to the wind stack 24. The blower or cleaning fan 24 furnishes an even blast through the lower chaffer 26, the adjustable chaffer 22 and the auxiliary chaffer 10. While the lower chaffer is agitated by the arm 27 eccentrically driven from the fan 25. The shoe screen 28 takes out the foul seed and foreign matter and permits the grain to enter the grain auger 29 which delivers the grain to the elevator for sacking, while the grain carried by the blast of the fan 24 toward the stack fan 25 is prevented from going into the stack by means of the projecting ledge 30 which prevents the grain from sliding upward and over the bottom tray, but causes the grain to descend due to the baffle or wind board 31 and the grain reaches the tailing auger 32 which delivers the unthreshed heads to an elevator for return to the cylinder.

The rearward depending ends of the blade 11 have their lower edges bevelled at 33 to eliminate any obstructions with the chaffer extension 23. Obviously the auxiliary chaffer 10 as shown and described affords a positive means of separating the chaff from the grain before they contact the adjustable chaffer. In this manner it functions as a positive means of eliminating the building up or bunching of the chaff or straw joints which in some locations depending on the climatic conditions, presents quite a problem and is responsible for carrying a large quantity of grain with the chaff through the stacker. This grain naturally is lost.

I have entered into a detailed description of the construction and relative arrangement of parts embraced in the present and preferred embodiments of my invention in order to impart a full clear and exact understanding of the said embodiments. I do not desire to be understood however as confining myself to the said specific construction and relative arrangement of parts inasmuch as in the future practice of my inven-

tion various changes and modifications may be made such as fall within the scope of the appended claims.

Having thus described my invention what I claim and desire to secure by Letters Patent in the United States is:

1. An auxiliary chaffing device adaptable for use with a threshing mechanism of a grain separator incorporating a conveyor and chaffer, said device comprising a plurality of horizontal blades 10 disposed parallel to one another, said blades being of various lengths arranged in a manner to provide sections in the device in which the blades are gradually spaced at various distances apart from one another, the depending end of said blades providing the greatest space between them, support rods disposed at right angles to said members, sleeves disposed for engagement with said rods for spacing said blades, all of said blades provided with upwardly extending projections and means for horizontally suspending said device parallel to the conveyor in said separator and at a slight distance above the chaffer in said separating mechanism.

2. A device as described in claim 1 in which the horizontal blades are rigidly attached to said support rods in spaced relation to one another.

3. In combination with a grain threshing mechanism, of a grain separator incorporating a conveyor and chaffer, an auxiliary chaffing device of the character described comprising in combination a plurality of blades disposed parallel to one another said blades being of various lengths arranged in a manner to provide graduated sections in the device in which the blades are at various distances apart from one another, the depending ends being the farthest apart, support rods disposed at right angles to said blades the depending ends of the longest blades being cut at an angle and corrugated to provide rigidity and means for supporting said device horizontally so that its one end is at a level with the conveyor in the separating mechanism, the other end raised at slight angle at a slight elevation above the adjustable chaffer in said separating mechanism.

ADOLPH WOELERT.
